COMBINED VANITY CASE AND FLASHLIGHT

Patrick Mailloux, West Warwick, R. I.

Application February 25, 1936, Serial No. 65,698

1 Claim. (Cl. 240—6.45)

This invention pertains to new and useful improvements in devices for personal use and more particularly to a combined flashlight and vanity case.

5 The principal object of the present invention is to provide a vanity case wherein a light is employed to permit the user to see herself in a dark place and wherein this case has the light so arranged that the same can be employed as a 10 flashlight for purposes extraneous to the use of the case for toilet purposes.

Other important objects and advantages of the invention will become apparent to the reader of the following specification.

15 In the drawings:

Figure 1 represents a perspective view showing the case in open position.

Figure 2 represents a vertical sectional view through the case with the top in partly open 20 position.

Figure 3 is a sectional view taken substantially on the line 3—3 of Figure 2.

Figure 4 is a cross sectional view taken substantially on line 4—4 of Figure 2.

25 Referring to the drawings wherein like numerals designate like parts, it can be seen that the device includes a rectangular shaped case 5 having the swingable back wall 6 and the stationary front wall 7, the front wall 7 having the centrally located opening 8 therein.

Hingedly connected to the end 6 of the case 5 is the cover 9 within which the mirror 10 is mounted. This lid 9 is provided with a swingable plate 11 at its free end having a spring catch 12. This plate 11 can be swung down over the window 8 and the catch 12 can engage under the adjacent end of the case and preferably over the small protuberance 13. (See Figure 2.)

40 The swingable rear wall 6 is also provided with a spring catch 14 for engaging under a small protuberance 15 on the bottom of the case 6.

The case 6 is divided by the partition 16 into upper compartments 17 and 18 and this partition 16 is further formed into the lipstick and 45 eyebrow pencil troughs 19—20.

The compartment below the partition 16 is denoted by numeral 21 and is intended to receive the flat electric battery 22. A spring 23 between the rear wall 6 and the base end of the battery 22 serves to urge the contact 24 of the

battery against the center contact of the bulb 25 situated behind the frosted window 26 in the opening 8 of the front wall 7 of the case. A combined socket and reflector construction 27 is located rearwardly of the window 26 and supports the bulb 25 and this reflector 27, the bulb 25 and the window 26 are all located between the small side compartments 28 which may be employed for containing perfume or similar toilet articles for cosmetics and these compartments 28 are provided with slidable closures 29—29.

5 The powder and rouge compartments 17—18 are provided with covers 30.

One side wall of the case 6 is slotted as at 31 15 and a push button 32 connected with the metallic case 6 can be urged inwardly to engage the spring contact 33 which extends to the thread portion of the bulb 25.

Obviously when the bulb 32 is pushed inwardly and engages the spring 33, a circuit is completed through the lamp 25 and battery 22.

The cover 9 can be disposed in the position shown in Figure 1 so that the mirror 10 can be employed and the light from the bulb 25 will illuminate the features of the person using the device so that the user's features will be very clear in the mirror. When the device is to be used as a flashlight, the top 9 is thrown down and the plate 11 thrown laterally so that light 30 can pass through the windows 26.

While the foregoing specification sets forth the invention in specific terms, it is to be understood that numerous changes in the shape, size, materials may be resorted to without departing 35 from the spirit or scope of the invention as claimed hereinafter.

Having described the invention, what I claim as new is:

A toilet article comprising a case having a 40 swingable top, a mirror at the inside of the top, a lamp mounted in the case under the free end of the top, a window in the case at the end thereof adjacent the lamp through which light from the lamp can pass, a plate hingedly connected to the free end of the top and provided with a spring detent for engagement under the case to secure the top to the case when the plate is disposed across the front of the said window. 45

PATRICK MAILLOUX. 50
